UNITED STATES PATENT OFFICE.

LOUIS H. PERLMAN, OF NEW YORK, N. Y., ASSIGNOR TO GENERAL MOTORS CORPORATION, A CORPORATION OF DELAWARE.

RIM.

Application filed November 1, 1919. Serial No. 334,918.

To all whom it may concern:

Be it known that I, LOUIS H. PERLMAN, a citizen of the United States, residing at New York, in the county of New York and 5 State of New York, have invented certain new and useful Improvements in Rims; and I do hereby declare the following to be a full, clear, and exact description of the invention, such as will enable others skilled in 10 the art to which it appertains to make and use the same.

This invention relates to improvements in demountable rims, and more particularly to the cross-cut type of such rims.

15 The object in view is the provision of a rim structure designed to facilitate easy and quick application and removal to and from a tire casing.

With this and further objects in view as 20 will in part hereinafter become apparent and in part be stated, the invention comprises certain novel constructions, combinations and arrangements of parts as will be subsequently specified and claimed.

25 In the accompanying drawings,—

Figure 1 is a transverse axial section through a fragment of a wheel supplied with a demountable rim embodying the features of the present invention.

30 Figure 2 is an inverted plan view of the rim detached.

Figure 3 is a view similar to Figure 1 of the rim detached in the course of operation and substantially midway between the position 35 of collapse and the position of extension.

Figure 4 is a view similar to Figure 3 with the parts shown in full lines in the 40 fully collapsed or coiled position and in dotted lines in the position of collapse as far as is possible while the operating handle is in engagement with the actuating lever.

Figures 5 and 6 are transverse sections taken, respectively, on the planes indicated 45 by lines 5—5 and 6—6 of Figure 1, the rim structure only being shown.

Figure 7 is an edge view of the operating tool, a portion of the handle being broken away for the saving of space.

50 Figure 8 is a top plan view thereof. Referring to the drawings by numerals, 1 indicates a wheel body, parts thereof being broken away and the felly of which carries the usual felly band 2 having the supporting stop flange 3 adapted to receive and

sustain one edge of the demountable rim 4. The rim 4 is in operation sustained at the other edge by the usual side wedges, not shown, which stresses the rim 4 laterally against the flange 3 and radially away from the wheel body tending to expand the rim 4. Rim 4 is transversely cut at the place indicated at 5, and the ends of the rim are connected by an operating lever 6. The lever 6 is pivoted at the extreme end of one end portion of the rim 4 and is pivoted to the other end portion at a distance from the extreme end sufficient to insure the requisite collapsing or coiling action when the rim ends are to be moved past each other for reducing the effective diameter of the rim. To this end, a pintle 7 is carried by an intermediate portion of the lever 6 and extends through an eye 8 formed on the extreme end of one end portion of rim 4. The pintle 7 60 65 70 75 80 consists preferably of a rod extending for the greater portion of the width and transversely of the lever 6, the lever 6 being preferably in the form of a flat elongated plate of a width only slightly less than the width of the base of rim 4. The end portions of the rod comprising pintle 7 are turned inward, extended through the plate making up lever 6, and are riveted in engagement with said plate. Thus the pintle 7 is elongated and disposed to lie along the edge of the engaged end of rim 4, and the eye 8 is correspondingly elongated, being preferably formed by a strap of relatively thin sheet metal folded about and spaced from the respective end of rim 4 with the two sheets of the fold arranged one at each face of and fixed to the base of the rim 4. The manner of securing the sheet making up eye 8 may be varied considerably without deviation 90 95 100 105 from the invention, but by preference I employ spot welding as indicated at 9, 9. The material of the base of the rim at the end engaged by eye 8 is preferably notched in, as at 10, to accommodate the pintle 7 and eye 8 practically flush with the line of the cut 5. One end of lever 6 is provided with an eye 11 similar in construction and arrangement to the eye 8, the eye 11 surrounding a pintle 12 whose end portions are turned outward and riveted to the base of the rim 4 spaced from the extreme end of the respective end portion. Thus an intermediate portion of lever 6 is pivoted to one extreme end of rim 4 while the extreme end

110

of lever 6 is pivoted to the other end portion of rim 4, so that when the lever 6 is swung upon its pivotal connections after the manner indicated in Figures 3 and 4, 5 the end portions of the rim 4 are caused first to separate radially and then to move to a collapsed and lapping position, so that the rim structure is in fact partially coiled. Thus the rim is caused to have a diameter 10 proportionally less than when the rim is extended, that is, ready for use. When collapsed or coiled, the rim is of sufficiently small diameter for readily receiving a tire shoe or casing with inextensible or non- 15 elastic marginal beads. The operation of applying a collapsed cross-cut rim to and removing it from such a shoe or tire casing is well understood in the art and the application and removal of the shoe to the present 20 improved rim is substantially the same operation as that to an ordinary cross-cut rim in a collapsed condition.

The space between the inner face of rim 4 and the outer face of felly band 2 is limited 25 for various well understood reasons, and it is, therefore, desirable to so arrange and construct the parts of the present improved rim as to avoid necessity for increasing this space. To this end, the base 30 of rim 4 near the cut 5 is stamped out at 13, 13, so that a shallow recess is formed in the inner face of the rim of an area approximately equal to that of the lever 6 into which recess portions of the lever and the 35 connections thereof lie when the rim is in its extended condition, as seen in Figure 1.

To relieve the pintles 7 and 12 and the eyes 8 and 11 from the expanding stress on rim 4 due to the action of the side wedges, 40 I prefer to provide stops or drivers 14, 14, outstanding from the felly band 2 and spaced apart a distance equal substantially to the length of the lever 6 with its eye 11, so that in operation when the rim 4 is applied 45 on the wheel the eye 11 rests in contact with one of the drivers or stops 14, while the other driver or stop 14 engages the opposite extreme of lever 6.

It is apparent, of course, that difficulty 50 will be experienced in any effort to provide a lever 6 of a length sufficient in itself to enable manual operation of the lever in shifting the rim from its extended to its collapsed condition and conversely. Therefore, the free end portion of lever 6, that 55 is, that portion of lever 6 which extends at the opposite side of pintle 7 from that provided with eye 11, is constructed to receive an operating tool which in fact is a mere lengthening of the lever. The tool receiving features of the free end portion of the lever 6 are susceptible of wide variation, but consist preferably of the simplest practical means of attachment for an extension 60 tool, such, for example, as an under-cut slot

or elongated notch 15, the under-cut being produced by a rabbet 16 extending about the margin of the notch 15 at the outer face of lever 6. An aperture 17 is preferably formed in the lever 6 in line with the 70 notch 15 to provide a further means of engagement for the operating tool or extension handle. The operating tool consists of a handle 18 of any preferred length having an offset section 19 arranged for enabling the terminal, curved end portion 20 to lie in the median line of the rim while the handle 18 extends along and spaced from one edge of the rim. The curved end portion 20 is provided with a pin 21 which forms simply an outstanding boss and is also provided with a button 22, the latter being connected preferably in the same manner as the pin 21 to the end portion 20 and in line therewith. The operating 75 tool is applied after the manner indicated in Figure 3 by sliding the button into the notch 15 until the shank of the button strikes the inner end of the notch, and then swinging the lever until the stud or pin 21 extends into the aperture 17. The lever 6 is then ready to be operated by the extension handle. The handle having thus been applied and the parts being in the position indicated in Figure 2, the handle 18 is 80 swinging to the position indicated in dotted lines in Figure 4. During this movement the lever 6 causes the ends of the rim 4 to separate and move through certain areas with respect to each other such as to bring 85 them to the position indicated in Figure 3, and then down to the position indicated in dotted lines in Figure 4. The lever 18 may then be withdrawn and the rim ends will move to the position indicated in full lines in 90 Figure 4. This last movement is due to the spring action of the rim as a whole, and is effected of itself without the aid of the operator. The rim is then in position to have a shoe removed from it or to have 95 a shoe applied thereon. After application of the shoe, the rim is restored to its extended condition by a converse movement 100 to that just described. In some instances it may be desirable to leave the tool 20 applied to the lever 6 during the removal and application of a shoe in which event the rim ends will remain in that relation to 105 each other indicated by the dotted lines in Figure 4.

I claim:—

1. In a rim structure for use upon a vehicle wheel, the combination of a cross-cut demountable rim, an operating lever for the end portions of the rim, a pintle fixed to the lever and extending along the cut edge of one end of the rim, an eye fixed to the rim and surrounding said pintle, a pintle fixed to a part of the other end portion of the rim and extending along the edge 110

of the end of the lever, and an eye fixed to the lever and surrounding the last-named pindle, the last named eye and the opposite end of the lever being adapted to cooperate with driving lugs upon the wheel.

2. In a rim structure for use upon a vehicle wheel, the combination of a cross-cut demountable rim, and a lever hinged intermediate its ends to one terminus of 10 the rim and hinged to an intermediate portion of the rim at one terminus of the lever, the free end portion of the lever having an undercut notch and an eye for receiving the engaging parts of an extension handle 15 and being adapted to cooperate with a driving lug upon the wheel.

3. In a rim structure, the combination of a cross-cut demountable rim, a lever for manipulating said rim, the lever being of 20 a thickness equal substantially to the thickness of the rim and adapted, when inactive, to lie along and substantially in contact with the inner face of the base of the rim, a pindle extending along the line of the cut 25 edge of the rim and of a thickness equal

only approximately to the thickness of such cut edge, the said pindle being anchored to the lever at an intermediate point in the length thereof, a strap of relatively thin material extending about said pindle and 30 being fixed to the rim for effecting a hinged connection of the pindle to the rim along the line of the cut edge thereof, a pindle extending along the line of the edge of one end of the lever and of a thickness equal only approximately to the thickness of the lever, said pindle being anchored to that end portion of the rim opposite the end portion engaged by the first-mentioned pindle and spaced therefrom, and a strap 35 of relatively thin material extending about the second-mentioned pindle and fixed to the lever for hinging the end portion of the lever to the rim.

In testimony whereof I affix my signature 40 in presence of two witnesses.

LOUIS H. PERLMAN.
